UNITED STATES PATENT OFFICE.

ALEXANDER E. FOGELQUIST, OF MINNEAPOLIS, MINNESOTA, ASSIGNOR TO NORTH-WESTERN BAKERS SUPPLY CO., OF MINNEAPOLIS, MINNESOTA, A CORPORATION.

FLEXIBLE DOOR.

1,396,414.

Specification of Letters Patent. Patented Nov. 8, 1921.

Application filed January 21, 1918. Serial No. 212,958.

To all whom it may concern:

Be it known that I, ALEXANDER E. FOGELQUIST, a citizen of the United States, resident of Minneapolis, county of Hennepin, 5 State of Minnesota, have invented certain new and useful Improvements in Flexible Doors, of which the following is a specification.

The object of my invention is to provide a 10 folding or flexible door adapted for use generally wherever it is desired to use a door of this type and particularly suitable for cabinets of various kinds where it is essential to exclude dust and dirt from the interior, eliminate the use of material which might become unsanitary or cause objectionable odors in the cabinet, and at the same time present a neat, ornamental appearance when in use.

20 The invention consists generally in various constructions and combinations, all as hereinafter described and particularly pointed out in the claims.

In the accompanying drawings forming 25 part of this specification,

Figure 1 is a front elevation of a cabinet embodying my invention,

Fig. 2 is an end elevation, partially in section, of the same,

30 Fig. 3 is a detail sectional view, showing the guides and a portion of the counter-balance for the cabinet door,

Fig. 4 is a vertical sectional view, showing 35 the sections of the door and the manner of uniting the longitudinal edges of these sections.

Fig. 5 is a sectional view, showing a modified construction,

Fig. 6 is a sectional view on the line 6-6 40 of Fig. 4.

Fig. 7 is a sectional view on the line 7-7 of Fig. 4.

In the drawing, 2 represents the base of 45 the cabinet, having suitable castor wheels 3. The frame of the cabinet is supported on said base and comprises upright standards 5 at the corners of the frame and angle bars 6, substantially U-shaped in form, secured to the standards on each side of the cabinet. 50 The upright standards are recessed at 8 and these recesses are inclosed on two sides by the flanges of the angle bars 6. At the top of the standards cross bars 9 are provided, on which U-shaped castings 10 are secured 55 to coöperate with the angle bars 6 to form

curved guide-ways 11 extending over the top of the cabinet, the vertical portion of said guide-ways extending from the bottom of the cabinet upwardly to the top of the standards, being formed by the angle bars 60 6 and the walls of the recesses 8. The standards are also provided with vertical ribs 12 having a covering of sheet metal 13 between which and the inner edges of the angle bars 6 the flexible door of the cabinet is adapted 65 to slide. This door is composed of a series of sheet metal sections 14. One longitudinal edge of each section is folded inwardly and upwardly upon itself to form a double thickness 15 running lengthwise of the section. 70 The edge is then bent inwardly to form a flange 16 and downwardly forming a flange 17, a rib 18 at the extremity of the flange 17 being inwardly and upwardly turned, forming a hook-like projection on the section 75 extending from end to end thereof, a narrow gap or opening being formed between the rib 18 and the part 15. The other longitudinal edge of the section is provided with an inwardly turned flange 19 terminating in a 80 downwardly turned lip 20 that is adapted to enter the gap between the parts 15 and 18 and interlock with the flange 17 and the lip 18, and thereby hold the two abutting sections together while allowing them to rock. 85 The connection between the sections will be concealed from the front of the cabinet and will so break the joint between the abutting sections that the entrance of dust and dirt through the door will be prevented.

In assembling the sections, the flanged ends are interlocked by engaging the flange on one edge of a section with the flange on the adjacent edge of the abutting section 95 and moving them longitudinally one upon the other. The sections bear on the rib 12 of the upright standards in their vertical movement and in making the turn at the top of the cabinet they will ride on the edge of 100 the castings 10, being held in place thereon by the curved sections of the angle bars.

As a metallic door of this type would be quite heavy, I prefer to provide counter-balances therefor comprising cables 21 passing over sheaves 22 having weights 23 at one end and attached to ears 24 secured to the lower section of the door. The upward pull on this lower section will engage the flange 19 at its upper edge with the flange 16 of 110

the section above and exert a lifting force thereon to hold the door in any position in which it may be adjusted. This lower section is also provided with suitable lifting handles 25. Within the cabinet suitable shelves 26 are provided for pies, cakes or different articles which it may be desired to place thereon.

In Fig. 5 a modified construction is shown, 10 which consists in providing belts 27 mounted on sheaves 28 in the upper part of the cabinet, said belts forming anti-friction surfaces on which the door sections may ride and slide. These belts will take the place of 15 the ribbed casting 10 in the top of the cabinet.

I claim as my invention:

1. The combination, with a casing having curved guideways, of a vertically sliding door therefor composed of a series of longitudinal sections, each section having one longitudinal edge inwardly and upwardly turned upon itself against the wall of the section and then outwardly and downwardly 25 turned to form a flange and terminating in an upwardly projecting lip, the other longitudinal edge of said section being inwardly and downwardly turned and having an end

portion to fit between said flange and said upwardly projecting lip on the edge of the 30 adjacent section, said end rocking in the angle between said flange and lip and allowing the ends of said sections to accommodate themselves to the curve of said guideways.

2. The combination, with a casing having 35 guideways therein, of a door mounted to slide in said guideways and composed of a series of longitudinal sections, each section having one edge inwardly and upwardly turned upon itself against the wall of the 40 section and then outwardly and downwardly turned to form a flange and terminating in an upwardly projecting lip, the other longitudinal edge of said section being inwardly and downwardly turned on the same 45 side of the section and terminating in an end that is adapted to fit the angle between the flange and lip of the adjacent section and rock in said angle during the movement of the door in said guideways, and counter-balance cables connected to the lower portion of said door.

In witness whereof, I have hereunto set my hand this 29th day of December, 1917.

ALEXANDER E. FOGELQUIST.
